(57) **CLAIM**

The ornamental design for an inflation valve of hemostasis device as shown and described.

DESCRIPTION

FIG. 1 is a front perspective view of an inflation valve of hemostasis device showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is the inflation valve of hemostasis device of FIG. 1 shown in a first position of use;

FIG. 10 is the inflation valve of hemostasis device of FIG. 1 shown in a second position of use; and,

FIG. 11 is the inflation valve of hemostasis device of FIG. 1 shown in a third position of use.

The broken lines shown in FIGS. 1 to 6 and FIGS. 8 to 11 represent portions of the inflation valve of hemostasis device and form no part of the claimed design.

The broken lines shown in FIGS. 9 to 11 represent environments and form no part of the claimed design.

1 Claim, 11 Drawing Sheets
